UNITED STATES PATENT OFFICE.

WOLFGANG E. SCHWARZMANN, OF LONGMEADOW, MASSACHUSETTS, ASSIGNOR TO AMERICAN BOSCH MAGNETO CORPORATION, OF SPRINGFIELD, MASSACHUSETTS, A CORPORATION OF NEW YORK.

ADJUSTABLE INTERRUPTER CAM.

1,426,609.

Specification of Letters Patent. Patented Aug. 22, 1922.

Application filed January 11, 1921. Serial No. 436,625.

To all whom it may concern:

Be it known that I, WOLFGANG E. SCHWARZMANN, a citizen of the United States, residing at 51 Belleclaire Avenue, 5 Longmeadow, in the county of Hampden, State of Massachusetts, have invented certain new and useful Improvements in Adjustable Interrupter Cams; and I do hereby declare the following to be a full, clear, 10 and exact description of the invention, such as will enable others skilled in the art to which it appertains to make and use the same.

The present invention relates to timing 15 mechanism for magnetos, and particularly to that having a timing ring carrying interrupter cams and a timing arm.

The adjustable member of the interrupter is ordinarily in the form of a ring carrying 20 cams which are periodically engaged by the deflectable element of a pair of rotating contact carrying elements. These cams have heretofore been positioned and fastened in fixed relation in the adjustable member or 25 cam ring by the manufacturer of the interrupter. When installing and testing the timing relation it frequently occurs that the position of the cams with relation to the ring is not the best to suit the particular 30 engine installation, or in the course of operation it may be found that the ends of the cams have become worn so that the interrupter contacts are slightly late in separating the interrupter contacts and breaking the 35 primary circuit of the ignition system.

With the above in view, it is an object of my invention to adjust the interrupter cams with angular relation to the cam ring, and, therefore, in accordance with one part 40 of my invention, the cam ring and the cams have adjustable means, preferably in the form of slots in the cam ring and securing means passing through and adjustable along the slots, for securing the cams in adjusted 45 position, so that the impacting of the cams may be advanced or retarded to the position which will effect a correctly timed operation of the deflectable element of the contact carrying elements of the interrupter mechanism, the connecting means having means to continually cover the apertures so as to exclude access of foreign matter to the cams and entry thereof into the interrupter mechanism.

As another part of my invention a cam 55 and a shoe respectively engages with the inner and outer surfaces of the cam ring and are connected by a connecting means extending through and movable along an elongated aperture provided in the cam ring 60 between the cam and shoe so that relative adjustment between the cam and the cam ring is obtained, the shoe also constantly covering the aperture so as to exclude access of foreign matter to the cams and entry 65 thereof into the interrupter mechanism, and the connecting means being operable, after adjustment of the cam is made, to rigidly secure the cam in adjusted position.

In the accompanying drawing illustrating 70 the preferred embodiment of the invention:

Fig. 1 is an end view of the timing ring and timing arm with the adjustable cams in position; Fig. 2 is a side view thereof; Fig. 3 is a top plan view thereof; Fig. 4 75 is a view similar to Fig. 3 showing the elongated aperture through which the connecting bolt passes; Fig. 5 is a fragmentary sectional view taken on line 5—5 of Fig. 3; and Fig. 6 is a fragmentary sectional view 80 taken on line 6—6 of Fig. 3.

Referring more particularly to the drawing, an adjustable timing device constructed in accordance with my invention comprises a cam ring 1 to which is secured a timing 85 arm 2 by suitable securing means 3, such as screws or rivets. The cam ring has an annular peripheral groove or recess 4 and a pair of elongated apertures 5 piercing through the cam ring in the bottom of the 90 recess 4. On each side of each aperture 5 is located a cam 6 and a shoe 7 connected together by a screw bolt 8 passing through the aperture, the cam 6 having a curved surface 9 corresponding to the inner surface 95 of the cam ring and in engagement therewith, and the shoe 7 having a curved surface 10 corresponding to the curvature of the bottom of the recess 4. The bolt 8 is capable of longitudinal movement along 100 the aperture 5 whereby the cam 6 and the shoe 7 are capable of angular adjustment about the axis of the cam ring to the extent of the movement of the bolt 8 permitted by the length of the aperture 5. The shoe 105 7 is of generally rectangular form with the lateral edges 11 thereof in engagement with or abutting against the shoulders 12 of the

annular groove or recess 4 so as to prevent the turning of the shoe 7 during the adjustment of the cam 6 relative to the cam ring 1. The outer end of the bolt 8 receives a 5 nut 13 between which, and the shoe 7, is interposed a washer 14 of any suitable material.

When it is desired to adjust the position of the cam or cams 6 angularly with respect 10 to the cam ring 1 the nut 13 may be loosened and each cam 6 together with the bolt 8, shoe 7, washer 14 and nut 13 are moved so as to slide the cam 6 along the inner surface of the ring 1 and the shoe 7 along the 15 annular recess or groove 4 to the extent desired and then the nut 13 is tightened whereby the cam 6 and the shoe 7 are caused to bind against the inner surface of the cam ring and the bottom of the groove 4, 20 respectively, and thus maintain the same rigidly in adjusted position.

The shoe 7 is also of such a size as to completely cover the aperture 5 at any adjusted position thereof so as to prevent access of foreign matter to the cam 6 and the entry thereof into the interrupter mechanism. The side walls 12 of the annular recess or groove 4 are continually in engagement with the lateral edges 11 of the shoe 7 30 during the adjusting movement of the latter whereby the shoe 7 is prevented from turning about the axis of the bolt 8, thus maintaining the curved surface 10 of the shoe in proper relation with the curved bottom of 35 the recess 4.

Having thus described my invention what I claim is:

1. In a timing mechanism for magnetos, the combination of a cam ring, an interrupter cam, said ring having an elongated aperture, and securing means passing through and adjustable along said aperture for securing said cam in adjusted position. 40

2. In a timing mechanism for magnetos, the combination of a cam ring having a timing arm secured thereto, interrupter cams, said ring having elongated apertures, and securing means passing through and adjustable along said apertures for securing said cams in adjusted position. 45

3. In a timing mechanism for magnetos, the combination of a cam ring having a timing arm secured thereto, interrupter cams, said ring having elongated apertures, and securing means passing through and adjustable along said apertures for securing said cams in adjusted position. 50

4. In a timing mechanism for magnetos, the combination of a cam ring having a timing arm secured thereto, interrupter cams, said ring having elongated apertures, and securing means passing through and adjustable along said apertures for securing said cams in adjusted position, said means having means for closing said apertures at all times for excluding foreign matter from said cams. 55

5. In a timing mechanism for magnetos, the combination of a cam ring having a timing arm secured thereto, an interrupter cam in engagement with the inner surface of said ring, a shoe in engagement with the outer surface of said ring, said ring having an elongated aperture between said cam and said shoe and adapted to be covered by said shoe, and connecting means extending through and movable along said slot and connected to said cam and shoe, whereby said cam is adjustable along the inner surface of said ring, said connecting means operable to rigidly secure said cam in adjusted position. 60

6. In testimony whereof I affix my signature. 65

WOLFGANG E. SCHWARZMANN. 70
